CLAIM

The ornamental design for a liquid heater which operates on solar energy or any other energy source, as shown and described.

DESCRIPTION

FIG. 1 is a front perspective view of a liquid heater which operates on solar energy or any other energy source, showing our new design;

FIG. 2 is a front elevation view thereof;

FIG. 3 is a top plan view thereof;

FIG. 4 is a front and side perspective view of a liquid heater which operates on solar energy or any other energy source showing a second embodiment of our new design;

FIG. 5 is a rear elevation view of FIG. 4;

FIG. 6 is a top plan view of FIG. 4; and

FIG. 7 is a detailed front perspective view of an evaporator panel, shown separately for clarity of illustration, which is wrapped on the outside of a liquid heater which operates on solar energy or any other energy source, the first embodiment having two evaporator panels, and the second embodiment having three panels.

FIG. 1.

FIG. 2.

FIG. 3.

FIG. 4.

FIG. 5.

FIG. 6

FIG. 7.
